SLIDE FASTENER STRINGER

Robert F. Andler, Rutherford, N. J., assignor to
Conmar Products Corporation, Newark, N. J.,
a corporation of New Jersey

Application March 18, 1943, Serial No. 479,572

3 Claims. (Cl. 24—205)

This invention relates to slide fasteners and more particularly to a slide fastener stringer designed for secure and neat attachment to garments or the like by a hot pressing operation.

A slide fastener stringer consists of a tape having a beaded edge and slide fastener elements attached along the beaded edge. The stringer is attached to a garment (or other article for which it is to form a separable fastener) by securing the tape to the edge portion of the garment. The tape is most commonly secured by sewing and less commonly by the use of adhesives. When secured by means of adhesives, the union effected is not strong, is subject to tearing away or stripping accentuated by repeated pulling due to slider operation and is generally unsightly.

The prime object of my present invention relates to the making of slide fasteners designed for adhesive attachment to the article to which it is to be applied, embodying the following features of structure and advantage:

1. The stringer tape is double-ply, the two plies being coated on their interior contiguous faces with the adhesive. The two plies form open wings which are adapted to receive therebetween, for adhesive attachment to the opposite faces of, an edge portion of the article for which it is to form a separable fastener. When attached, stripping or tearing away becomes impossible, the union is strong and practically permanent, and the closure (which may be to an unselvaged or unfinished garment edge) is neat and sightly.

2. The adhesive coatings on the interior faces of the open wings of the tape plies are normally dry coatings of a thermo-responsive adhesive. Thereby, the stringers may be handled and sold on the open market for consumer use. The consumer may attach the stringer to the garment simply by a hot pressing operation as by means of a hot iron. No sewing is necessary, nor is any further treatment needed;

3. The areas of the tape plies encompassed by the beaded edge and attached slide fastener elements are adhesively united (by the applied adhesive coatings) during the making of the beaded tapes. Thereby the manufacture of the beaded tape is simplified and its handling during the making of the stringer (attaching the slide fasteners to the beaded tape) and later when it is to be used by the consumer is facilitated; and

4. A well balanced structure is produced both in the stringer and in the resulting garment due to symmetry and uniformity.

To the accomplishment of the foregoing and

such other objects as may hereinafter appear, my invention is directed to the slide fastener stringer sought to be defined in the appended claims and described in the following specification taken together with the appended drawing in which:

Fig. 1 is a perspective view of the stringer showing one embodiment of my invention;

Fig. 2 is a view thereof taken in cross-section in the plane of the line 2—2 of Fig. 1 before attaching the fastener elements thereto;

Fig. 3 is a view of the same also taken in cross-section and shown on an enlarged scale and showing the manner of attaching the stringer to the edge portion of a garment or the like;

Fig. 4 is a view corresponding to that of Fig. 2 and showing the modification; and

Fig. 5 is a view corresponding to Fig. 3 of said modification.

- 20 Referring now more in detail to the drawing, the slide fastener stringer of my present invention comprises a double ply tape T having a beaded edge B and slide fastener elements f, f attached along the beaded edge, the two plies p' and p² of the tape T each being coated on their interior contiguous faces f' and f² with the adhesive coatings c' and c². The adhesive coatings c' and c² are preferably over the entire areas of the contiguous faces f' and f² of the tape plies.
- 25 30 The tape T is a textile fabric formed by folding a fabric sheet into the configuration best shown in Fig. 2 of the drawing, thus producing the folded edge 10 and the two plies p' and p². In the form of the invention shown in Figs. 1 to 3, two cords 12 and 14 are sewn by a line of stitching 16 to the folded edge 10 to form the beaded edge, and the fastening elements f, f are clamped on to the thus reinforced or beaded tape edge to produce the resulting structure shown in Fig. 3.
- 35 40 The adhesive coating is applied to one side of the textile fabric sheet preferably before the same is folded, and the adhesive employed is a thermo-responsive adhesive, that is to say, one that is either thermoplastic or thermosetting. In the form of the invention under discussion, the face of the fabric sheet is coated with a layer of a thermosetting resin. After the coating operation, the plies p' and p² are adhesively united over the area generally designated as a encompassed by the beaded edge B and the attached slide fastener elements, this being done by a suitable heating die. After this cementing operation, the beading cords 12 and 14 are attached. In the resulting tape structure shown in Fig. 2, the remaining areas of the tape plies remain free or

PRINTED IN U.S.A.

unattached and these free areas of the tape plies form normally dry adhesive coated open wings as shown in Fig. 2 of the drawing.

The thus constructed tape of Fig. 2 is used for making the stringer of Fig. 3 and the said stringer is then handled and may be marketed for use by the consumer ready for attachment to an edge portion 18 of a garment or other article in the manner depicted in Fig. 3. The normally open wings of the stringer are thus adapted to receive therebetween the edge portion 18 of a garment and attachment or union is effected by hot pressing as by means of a hot iron, the laminated arrangement thus produced. The hot pressing may be effected either by applying the iron to either side or both sides of the tape plies p' and p'' .

In the form of the invention shown in Figs. 4 and 5, the tape T' having the plies p^3 and p^4 is coated with a thermoplastic resin so that the entire face of the sheet fabric is provided with the layer of the thermoplastic resin. In this form of the invention the fabric sheet which forms the tape is folded at 20 around so as to embrace the beading cord 22. Sewing of this cord on the tape is dispensed with; the cord 22, suitably stretched, is instead cemented in place by heating in a die operating in the region around the cord. Thereby the plies p^3 and p^4 are not only adhesively united over the area a' which encompasses the beaded edge and the attached slide fastener elements, but the beading cord is secured in position by the adhesive. Fig. 4 shows the resulting tape as ready for use in making the stringers. Here again the tape has free or un-united areas which form normally dry adhesively coated open wings. The tape of Fig. 4 is then used to make a stringer as shown in Fig. 5 and as exemplified by Fig. 1 in which the contiguous faces of the open ply wings are coated at c^3 and c^4 with a thermoplastic resin which in the finished product is a normally dry adhesive coating. As before, this product may then be attached to an edge portion of the garment such as the edge portion 24 in a manner similar to that described in connection with Figs. 2 and 3 of the drawing.

This structure makes possible the use of strips slit from cloth instead of woven tapes. Any suitable cloth provided on one face with the adhesive can be slit to double width of the commonly used tape, folded, and further used like a woven double ply. The advantages are that such strips, obtained from cloth made on large looms, are less expensive than narrow tapes made on special looms, and that great lengths or widths of cloth can more easily be coated with adhesives than narrow separate strips. There would be no objection to using such slit strips because all the rough edges at the fold would be secured against fraying by the applied coating. In making the tape from either cloth or woven strips, instead of folding a strip of double width, the invention enables the use of two separate tape strips stuck or adhered together at one edge.

The slide fastener stringer of the present invention and the manner of making the same and the advantages thereof will in the main be fully apparent from the above detailed description thereof. A stringer product is produced which is

ready for use by the consumer for attachment to a garment without sewing and without treating either the garment edge or the tape in any way. By reason of the resulting construction as shown in Figs. 3 and 5, stripping or tearing away of the tape from the garment at the beaded edge is well nigh impossible; the union is strong and practically permanent. The edge portion 18 being wholly concealed by the attached tape may have an unselvaged or unfinished edge; the resulting closure is neat and sightly. The consumer may attach the stringer to the garment by a simple hot pressing operation. The preliminary uniting of the tape plies at the area a or a' simplifies the handling of the tape during stringer manufacture and facilitates the operation of adhesively attaching the same to a garment illustrated in Figs. 3 and 5 of the drawing. The symmetry of the arrangement shown in these figures is the means of producing a well balanced structure.

While I have shown the invention in the preferred forms, it will be apparent that changes may be made therein without departing from the spirit of the invention defined in the following claims.

I claim:

1. A slide fastener stringer comprising a double ply tape having a beaded edge and slide fastener elements attached along the beaded edge, the two plies of the tape being coated on their interior contiguous faces with an adhesive, the said plies being adhesively united over the areas encompassed by the beaded edge and attached slide fastener elements, and being free over their remaining areas, the free areas of the tape plies forming normally dry adhesively coated open wings adapted to receive therebetween, for adhesive attachment to the opposite faces of, an edge portion of a garment or the like.
2. A slide fastener stringer comprising a double ply tape having a beaded edge and slide fastener elements attached along the beaded edge, the two plies of the tape being coated on their interior contiguous faces with a thermo-responsive adhesive, the said plies being adhesively united over the areas encompassed by the beaded edge and attached slide fastener elements, and being free over the remaining areas, the free areas of the tape plies forming normally dry adhesively coated open wings adapted to receive therebetween, for adhesive attachment by hot pressing to the opposite faces of, an edge portion of a garment or the like.
3. A slide fastener stringer comprising a textile fabric folded to form a double ply tape having at the fold a beaded edge and slide fastener elements attached along the beaded edge, the two plies of the tape being coated on their interior contiguous faces with a thermo-responsive adhesive, the said plies being adhesively united over the areas encompassed by the beaded edge and attached slide fastener elements, and being free over their remaining areas, the free areas of the tape plies forming normally dry adhesively coated open wings adapted to receive therebetween, for adhesive attachment by hot pressing to the opposite faces of, an edge portion of a garment or the like.
